UNITED STATES PATENT OFFICE.

AUGUST TAUTGES, OF ANIWA, WISCONSIN, ASSIGNOR OF TWO-FIFTHS TO JOE LINDNER, JR., OF BIRNAMWOOD, WISCONSIN.

DOOR STRUCTURE FOR GRAIN-CARS AND THE LIKE.

1,242,268.

Specification of Letters Patent.

Patented Oct. 9, 1917.

Application filed March 17, 1917. Serial No. 155,481.

To all whom it may concern:

Be it known that I, AUGUST TAUTGES, a citizen of the United States, and resident of Aniwa, in the county of Shawano and State 5 of Wisconsin, have invented certain new and useful Improvements in Door Structures for Grain-Cars and the like; and I do hereby declare that the following is a full, clear, and exact description thereof.

10 My invention relates to new and useful improvements in doors, particularly those which are adapted to be used on railway cars to carry grain or the like, or it may be used in conjunction with other types of structures including buildings.

15 It is particularly the object of the present invention to greatly improve and simplify the door construction shown in my United States patent, Serial No. 105,534, filed June 20 24, 1916, by forming the same of a fewer number of parts so that the door may be more readily placed in seating relation with its door opening or removed therefrom to permit access to the grain car or the structure 25 in which the invention is used.

20 A further object of the invention is to provide a door carrying frame, with which doors of various different thicknesses may be used, for instance, very thin doors for 25 grain cars and very thick insulated doors for refrigerator cars and the like.

25 A still further object is to provide means in connection with the door carrying frame for holding the door, regardless of its thickness, in any one of several locked positions.

With these and other objects and advantages in view, the invention resides in the 30 novel features of construction, combination and arrangement of parts which will be 40 hereinafter more particularly described in the specification and claims and shown in the drawings, wherein:

Figure 1 is a side elevation of a portion of a railway car showing my improved door 45 construction applied thereto.

Fig. 2 is a vertical transverse section on the plane of the line 2—2 of Fig. 1.

In the accompanying drawing, although 50 the invention is shown used on railway cars, it is obvious that it is also adapted for use in connection with buildings and various other types of structures. Therefore it has been shown on a car and will be described in this connection merely for the sake of 55 illustration.

The car has a side wall 1 and a top 2, the eaves of which project beyond the side wall a sufficient distance to protect the door structure to a considerable extent from the weather, as will be evident from an examination of Fig. 2. The side wall is provided with a door opening 3, certain sides of which are inclined to be engaged by the similarly inclined edges of a door 4 which is supported by a suitable door carrying 60 frame 5.

A pair of track bars 6 and 7 are disposed above and below the door opening, they being spaced apart a sufficient distance to permit the door frame 5 to slide therebetween.

70 The door carrying frame is hung from the upper track 6 by a pair of hanger brackets 8 having flanged wheels 9 rotatably mounted therein to directly engage the track. The lower track bar 7 merely acts as a guide for

75 movement of the door carrying frame, and to prevent the same from swinging outwardly, said frame having a pair of U-shaped guide members 10 depending from its bottom to straddle said track 7. This

80 construction readily permits the frame 5, together with its door, to be slidably moved along the side wall of the car to completely clear the opening 3, or to be moved in the reverse direction until the frame engages

85 the stop 11, in which position the door may be readily moved inwardly to close the opening 3.

The door 4 is held within its frame 5 by 90 means of the links 12, two of which are provided for each side edge of the door. One end of each link is pivoted to the edge of

95 the door while its other end is similarly attached to the adjacent edge of the door carrying frame, and it will be seen from

Fig. 2 that the pivot members which connect the links to the frame are disposed in horizontal planes below similar planes passing through the pivot elements which attach the corresponding links to the door. In

100 this manner the door will be vertically raised when it is removed from its opening 3.

This peculiar manner of mounting the door within its frame permits the former to be moved to either side of the latter or held wholly within the opening in said frame.

Furthermore, the pivot elements which extend from the door 4 are disposed in a longitudinal plane passing through the center of said door, thereby allowing

the door carrying frame and its other parts to be positioned rather close to the side wall of the car. The considerable range of movement of the door is taken advantage of to 5 permit doors of various thicknesses to be used in connection with a door carrying frame of ordinary or standard size. In Fig. 2, a door of usual thickness is shown mounted in the door carrying frame, also in the 10 same figure is illustrated in dot and dash lines, a very thick door for use on refrigerator cars.

In moving the door 4 from its closed position, so that the frame may be slid beyond 15 the door opening, stops are preferably provided to prevent excessive outward movement of the door and also to aid a locking means to be hereinafter described, for holding the door in its several positions. When 20 the usual thin door, such as shown in full lines in Fig. 2 is used, pivoted stops 13 on the door carrying frame are swung into position to be engaged by the outer face of the door, as it is moved outwardly. Four or 25 more of these stops 13 are pivoted to the outer face of the frame 5, these stops being so constructed that they may be swung upwardly beyond the opening within the frame. They are held in their active position 30 by means of the studs 14 which rest in notches in one edge thereof. After having engaged the stops, the locking means, to be presently described, will hold the door rigidly within its frame and prevent either 35 inward or outward movement.

In case a refrigerator car door is used with this same door carrying frame and is to be moved outwardly to the dot and dash line position of Fig. 2, stationary stops 15 40 are provided for engagement thereby. These stops are preferably in the form of right-angled members secured to the inner edges of the opening in the frame 5, said stops projecting a considerable distance beyond 45 the outer face of the frame. The length of these stops 15 is dependent upon the thickness of the door, it being desirable to have the inner face of the door flush with the inner face of its frame as shown in Fig. 2.

50 The locking means for the door which is to be used for holding the same in either its closed, or any one of various open positions, consist of a pair of sliding locking bolts 16 preferably disposed substantially 55 transversely of the door. The inner ends of these bolts are pivotally connected to a lever 17 which is fixed to a short shaft 18 rotatably mounted in a suitable bearing extending through the center of the door. A 60 handle 19 is carried by the outer end of this shaft for rotating the same and to rock the lever 17. A handle 20 is pivotally attached to the inner end of the shaft and is adapted to hang downwardly as shown when not in 65 use. It is obvious that rotation of the shaft

in one direction will cause the bolts 16 to move away from each other to project their outer ends beyond the opposite side edges of the door, guides 21 on said door aiding the bolts in their sliding movements. When 70 the door 4 is disposed in seating relation with its opening and the bolts are slid outwardly, their free ends will be engaged in eyes 22 extending from the wall of the car. This will effectively lock the door in closed 75 position. The same sliding bolts if actuated in a like manner when the door has been moved outwardly into engagement with the stops 13 will be disposed in openings 23 formed in one arm of the stops 15. Additional openings 24 are also formed in the stops 15 to receive said sliding bolts when the door is moved to its most remote outward position or into engagement with the stops 15, in which case said stops 13 will 85 have been moved out of active position.

From the foregoing description, taken in connection with the accompanying drawing, it is obvious that a very simply constructed door carrying frame has been produced with 90 which doors of various thicknesses may be readily used, and that an improved arrangement of stops has been provided for co-operation therewith. Furthermore, the relatively few number of parts of which the 95 structure is composed will permit the same to be manufactured comparatively inexpensively and this feature also simplifies its operation to a considerable extent.

I claim:—

1. The combination with a wall having a door opening, of a door carrying frame slidably mounted adjacent the door opening, a door pivoted in said frame to swing to either side thereof or to be disposed in its longitudinal plane, and a locking means to hold the door in either of said three positions.

2. The combination with a wall having a door opening, of a door carrying frame slidably mounted adjacent the door opening, a door pivoted in said frame to swing to either side thereof or to be disposed in its longitudinal plane, and stops to be engaged by the door when in either of said three positions.

3. The combination with a wall having a door opening, of a door carrying frame slidably mounted adjacent the door opening, a door pivoted in said frame to swing to either side thereof or to be disposed in its longitudinal plane, stops to be engaged by the door when in either of said three positions, and locking means to hold said door in any one of its three positions when in engagement with said stops.

4. The combination with a wall having a door opening, of a door carrying frame slidably mounted adjacent the door opening, a door pivoted in said frame to swing to either side thereof, stops carried by the

100

105

115

120

125

130

frame to be engaged by the face of the door when the same is in various positions, one of said stops extending beyond the face of the frame farther than the other whereby doors of different thicknesses may be pivoted in the frame.

5. The combination with a wall having a door opening, of a door carrying frame slidably mounted adjacent the door opening, a 10 door pivoted in said frame to swing to either side thereof, a stop pivoted to the outer face of the frame, a second stop in the form of a right angular member secured by one arm to said frame, the other arm extending beyond the outer face of said frame, either of 15 said stops being adapted to be engaged by the outer face of the door, doors of different thicknesses being thereby operable in said frame and locking means for holding the 20 door in either of said positions when engaging either of said stops.

6. The combination with a wall having a door opening, of a carrying frame slidably mounted adjacent the door opening, a door

to be disposed in said opening, links pivoted 25 to opposite sides of said door and the sides of the frame adjacent thereof, said door being movable laterally and outwardly of said door opening to be disposed beyond the outer side of the frame or in the longitudinal plane thereof, stops for holding the door in the longitudinal plane of the frame, additional stops for holding the door beyond the outer side of said frame, and coöperating locking means on the door and frame 30 35 for securing the former in either of its last mentioned positions, said means being brought into operative relation when the door is moved laterally and outwardly on its links.

In testimony that I claim the foregoing I have hereunto set my hand at Aniwa, in the county of Shawano and State of Wisconsin, in the presence of two witnesses.

AUGUST TAUTGES.
